UNITED STATES PATENT OFFICE.

MARTIN L. MILLER, OF SEALY, TEXAS, ASSIGNOR OF ONE-THIRD TO W. I. HILL, OF SEALY, TEXAS.

CATTLE-GUARD.

SPECIFICATION forming part of Letters Patent No. 709,105, dated September 16, 1902.

Application filed June 28, 1901. Serial No. 66,449. (No model.)

To all whom it may concern:

Be it known that I, MARTIN L. MILLER, of Sealy, Austin county, Texas, have invented certain new and useful Improvements in Cattle-Guards, of which the following is a specification.

The present invention relates to cattle-guards for railways; and the object thereof is to provide an article of this character which will form an impassable barrier to cattle attempting to stray along the track, but will be out of the way of passing trains.

In the accompanying drawings the preferred form of the invention is clearly illustrated, and the construction and operation thereof is fully described in the following specification. It will of course be understood that this construction is open to such changes or modifications as the scope of the appended claims will permit.

In the drawings, Figure 1 is a perspective view of a cattle-guard constructed in accordance with the present invention. Fig. 2 is a longitudinal sectional view through the same. Fig. 3 is a cross-section taken on the line *xx* of Fig. 2, and Fig. 4 is a bottom plan view of the mechanism connecting the two intermediate elements. Fig. 5 is a detail view showing the construction of the bearings and stops for the outer platforms.

Similar numerals of reference designate corresponding parts in all the figures of the drawings.

In carrying out the invention an open space is provided beneath the railway-track, and this space is bridged by a suitable frame comprising sills 10 and intermediate supporting-beams 11, upon which the rails 12 are fastened. In this frame is mounted the guard.

In the space between the tracks is located a pair of normally horizontal members 13, preferably in the form of grids or gratings, said members having their inner ends spaced a slight distance apart and journaled upon the beams 11 by means of projecting pintles 14, that engage in suitable boxes 15, located upon said beams. The space between the adjacent ends of these members is closed by a plate 16, that is secured at its ends to the beams 11 between the journal-boxes 15. Each member is provided contiguous to its pivoted end with a

long and a short arm 17 and 18, the lower ends of said arms being bifurcated, as shown at 19. A curved link 20 is pivotally connected in the bifurcated end of the short arm 55 of one member and is pivotally and slidably mounted at its opposite end in the long arm of the other member. This latter connection is accomplished by providing a slot 21 in the link, through which the pivot-pin 22 of the 60 long arm passes. By this arrangement, although the two members are capable of an upward-and-downward movement, they are normally disposed in horizontal relation and counterbalance each other. When an animal steps upon one of the members, it will be depressed, and the long arm acting through the link connection upon the short arm of the other member will elevate said member to a degree greater than the corresponding depression of said first member, and the elevated member will form a barrier against the passage of the animal. The long arm of said elevated member will not interfere with this movement, as its lower end has a slidable 75 engagement with the other link. Should an animal attempt to pass in an opposite direction, the member above described as the barrier will constitute the operating member, and the former operating member will in 80 this instance form the barrier and be elevated. The comparatively great movement of the barrier member is accomplished by the arrangement of the several pivots, the distance between the pivot connection of the 85 link with the operating member and the pivot-axis thereof being greater than the distance between the pivot connection of the link with the barrier member and the pivot-axis of said barrier member. By this means 90 it will be seen that an exceedingly simple structure is provided which under normal conditions is completely out of the way of trains passing upon the tracks, but will form an impassable barrier to animals attempting 95 to stray along said track in either direction. Under certain conditions, however, it may only be needful to prevent the passage of cattle in one direction, in which case one of the links and its connections may be entirely dispensed with, and a structure with 100 this obvious omission will of course fall

within the scope of the claims. The spaces on the outside of the rail are covered by grated platforms 23, formed of spaced parallel bars 24, held a suitable distance apart 5 by spacing-blocks 25. These platforms are provided with a plurality of fulcrum-shafts 26, that project beyond the side edges of said platform and are seated in bearings 27, secured to the outer edges of the supporting-
10 beams 11 and the sills 10. These bearings are preferably in the form of plates secured to the upper faces of said beams and sills and have depressed portions that are located in suitable sockets in the beams. The ends 15 of the plates constituting the outer bearings are upturned and provided with terminal stop-hooks 28, which are engaged by the projecting ends of the shafts when said shafts are elevated through the corresponding de-
20 pression of the opposite ends of the platforms. By this arrangement it will be seen that no matter on which end an animal may step the opposite ends will be elevated; but the tilting movement of the platform will be lim-
25 ited by the projecting end of the elevated shaft coming into contact with the stop-hook.

From the foregoing it is thought that the construction, operation, and many advantages of the herein-described invention will 30 be apparent to those skilled in the art without further description, and it will be understood that various changes in the size, shape, proportion, and minor details of construction may be resorted to without departing from 35 the spirit or sacrificing any of the advantages of the invention.

Having thus described my invention, what I claim as new, and desire to secure by Letters Patent, is—

- 40 1. In a cattle-guard, the combination with a pivoted upwardly-movable barrier member, of a pivoted downwardly-movable operating member, a depending arm carried by the operating member, a depending arm carried 45 by the barrier member, and a single link pivotally connecting the arms of the members and movable therewith.
2. In a cattle-guard, the combination with a pivoted upwardly-movable barrier member, 50 of a pivoted downwardly-movable operating member, a depending arm carried by the operating member, and a link having a pivotal connection with the arm, said link being pivotally connected to the barrier member.

3. In a cattle-guard, the combination with 55 a pivoted upwardly-movable barrier member, of a pivoted downwardly-movable operating member, depending arms carried by the two members, the arm of the operating member being longer than that of the barrier member 60 and a link secured directly to said arms to simultaneously move them upon the depression of the operating member.

4. In a cattle-guard, the combination with 65 a pair of independent members movable in a downward and upward direction, of separate links pivotally connected with the members, each link having a slidable engagement with one member.

5. In a cattle-guard, the combination with 70 a pair of independent members movable in a downward and upward direction, each of said members having a depending arm, of links each being connected with one of the members and having a pivotal connection 75 with the arm of the other member.

6. In a cattle-guard, the combination with 80 a pair of independent members movable in a downward and upward direction, each of said members having a depending arm, and links 85 each being connected with one of the members, and having a pivotal and slidable connection with the arm of the other member.

7. In a cattle-guard, the combination with 85 a pair of independent members movable in a downward and upward direction, each of said members having depending long and short arms and a link pivotally connected at one end with the short arm of one member, the other end having a pivotal and slidable con- 90 nection with the long arm of the other member.

8. In a cattle-guard, a tilting platform having a plurality of fulcrums, and means arranged to engage the fulcrums to limit the 95 tilting movement of the platform.

9. In a cattle-guard, a tilting platform having a plurality of fulcrum-shafts projecting beyond the side edges thereof, a plurality of bearings for the projecting ends of the ful- 100 crum-shafts and stop-hooks located at the ends and above the bearings, said fulcrum- shaft ends engaging the hooks to limit the tilting movement of the platform.
